EMBORESSED METAL SHEET MATERIAL

Robert F. Nelson, Plainfield, N. J., assignor to Modern Engraving and Machine Company, Hillside, N. J., a corporation of New Jersey

Application August 13, 1957, Serial No. 47,356

Term of patent 14 years

(Cl. D54—2)

FIG.1.

FIG.2.

FIG.3.

FIG.4.

Figure 1 is a top plan view of an embossed metal sheet material embodying the novel design;

Figure 2 is an enlarged vertical sectional view taken along line 2—2 of Figure 1;

Figure 3 is a bottom plan view of the sheet material of Figure 1; and

Figure 4 is a vertical sectional view taken along line 4—4 of Figure 3.

I claim:

The ornamental design for embossed metal sheet material, as shown.
